[57] CLAIM

The ornamental design for a blender with pitcher and base components, as shown and described.

DESCRIPTION

FIG. 1 is a perspective view of a blender with pitcher and base components showing my new design;

FIG. 2 is a front elevational view thereof;

FIG. 3 is a side elevational view thereof taken from the right of FIG. 1;

FIG. 4 is a rear elevational view thereof;

FIG. 5 is a top plan view thereof;

FIG. 6 is a bottom plan view thereof;

FIG. 7 is a perspective view of the base component of the blender of FIG. 1;

FIG. 8 is a front elevational view thereof;

FIG. 9 is a side elevational view thereof taken from the right of the base component of FIG. 7;

FIG. 10 is a rear elevational view thereof;

FIG. 11 is a top plan view thereof;

FIG. 12 is a bottom plan view thereof;

FIG. 13 is a perspective view of the pitcher component of the blender of FIG. 1;

FIG. 14 is a rear elevational view thereof taken from the right of the pitcher component of FIG. 13;

FIG. 15 is a side elevational view thereof;

FIG. 16 is a front elevational view thereof taken from the left of the pitcher component of FIG. 13;

FIG. 17 is a bottom plan view thereof; and,

FIG. 18 is a top plan view thereof.
